SAXOPHONE KEY MOUNTING

Filed June 17, 1946

Heretofore in mounting keys of saxophones and similar instruments on the pivot posts, it has been the custom to use small screws which are threaded into the pivot post and have a reduced or plain pointed section extending into a recess of the pivot member. In order to provide for a smooth surface it has been the custom to counterbore the pivot post so the head of the screw head can be recessed in the post. This type of mounting requires much accurate machine work in forming the screws and in machining threads and a counterbore in the post, all of which requires much time and expense in the original manufacturing of the parts, and especially in repairing the keys

UNITED STATES PATENT OFFICE

SAXOPHONE KEY MOUNTING

Floyd E. Comer, Bristol, Ind., assignor to Buescher
Band Instrument Co., Elkhart, Ind.

Application June 17, 1946, Serial No. 677,126

4 Claims. (Cl. 84—385)

1

This invention relates to musical instruments of the wind type.

An object of this invention is to provide in a wind instrument, an improved pivotal mounting for the keys or levers.

Another object of this invention is to provide an improved pivot mounting for keys which will firmly hold the keys on the supporting posts but which will eliminate the usual pivot screws and will make easy the mounting or removal of the keys on the supporting posts.

A further object of this invention is to provide an improved pivot mounting wherein the parts are concealed and will not become loosened or broken under undue strain or stress.

A still further object of this invention is to provide an improved pivot mounting for keys on musical instruments as saxophones or the like which comprises a spring-pressed pivot member carried by the pivot rod engageable in an apertured pivot post in such a manner that the key assembly may be installed or removed without any special tools or without any special skill.

With the above and other objects in view, my invention consists in the arrangement, combination and details of construction disclosed in the drawings and specification, and then more particularly pointed out in the appended claims.

In the drawings:

Wherein similar reference characters designate similar parts throughout the respective views,

Figure 1 is a top plan view of a key of a musical instrument mounted with a pivot constructed according to an embodiment of this invention,

Figure 2 is a top plan view of a different key mounted on a pivot of this invention,

Figure 3 is a vertical section taken on the line 3—3 of Figure 1,

Figure 4 is a section taken on the line 4—4 of Figure 2.

Heretofore in mounting keys of saxophones and similar instruments on the pivot posts, it has been the custom to use small screws which are threaded into the pivot post and have a reduced or plain pointed section extending into a recess of the pivot member. In order to provide for a smooth surface it has been the custom to counterbore the pivot post so the head of the screw head can be recessed in the post. This type of mounting requires much accurate machine work in forming the screws and in machining threads and a counterbore in the post, all of which requires much time and expense in the original manufacturing of the parts, and especially in repairing the keys

2

where the screws and posts had to be individually made and fitted.

As there are several different length hinge tubes used on each instrument, the method of mounting each is slightly different from the others. The conventional method of mounting the hinge tubes of short length has been to run a screw through one post, through the hinge tube, and screw it into the opposite post. On the longer types, the conventional construction has been to have a conical type of pivot screw screwed into the knob at each end of the key, the conical portion extending into the key rod or hinge tube.

By using a construction as set forth in this invention, the difficult and expensive machining is eliminated in both the screws and post thereby reducing the manufacturing and maintenance costs and providing a more suitable mounting.

Referring to the drawings, the numeral 10 designates generally a tubular body of a musical instrument such as a saxophone or like instrument upon which is mounted a key 11. The key 11 is mounted on a hinge tube or rod 12 by brazing or other suitable attaching means and operates as a lever for opening the valves 14 which are also fixed to the rod 12. In the drawings, Figures 1 and 3 show the mounting for the long type of key rod 12, while Figures 2 and 4 depict the short hinge tube 12a.

For supporting the key rod 12 there is provided a pair of supporting posts 15 which are fixed on the body 10, one at each end of the rod 12. The posts 15 are formed with a rounded knob 16 at the upper end thereof. The knob 16 is formed with an outwardly diverging frusto-conical opening 17 on one side thereof and a small drilled passage 18 extending from the apex of the opening 17 through the knob 16.

The key rod 12 is formed with a lengthwise bore 19 at each end thereof, concentric with the rod 12. Enclosed within the bore 19 is a spring 20 and a pivot pin 21 slidably therein. The spring 20 is between the inner end wall of the bore 19 and the inner end of the pin 21 for constantly urging the pin 21 outwardly. The pin 21 is formed of a cylindrical member having a flat inner end and a rounded tapered outer end, the outer end being engageable in the opening 17 of the post 15.

For shorter key mountings, a tube or hinge tube 12a is more applicable, and a pair of opposed pivot pins 21 are slidably therein having a spring 20 disposed between the inner flat ends of the pins 21 for urging the pins 21 outwardly with respect to each other and the tube 12a.

In the use and operation of this type of mounting, the spring 20 and pins 21 are inserted into the hinge 12 or 12a, then one pin is engaged in the opening 17 of its supporting post 15, then the other pin 21 is pressed inwardly by the fingers of an operator and the hinge 12 is placed in position at which time the springs 20 will press the pins 21 into their respective positions in the openings 17.

For removing the hinges 12 and 12a, it is necessary to push a pin or other thin instrument through the opening 18 to press the pin 21 within the tube 12a or bore 19 and then raise the end of the tube or rod until it is disengaged from the knob 16. The pins 21 in the long rod 12 must be pressed in farther than in the short tubes 12a, so to prevent the pin or removing tool from sliding on the rounded end of the pin 21, there is provided a small bore 22 in the rounded end thereof in which the removing pin may be engaged while pushing the pivot pin 21 into the bore 19.

It may be desirable to employ two different types of key mounting pins for supporting the tube 12 on the posts 15. As an example, a conventional pivot screw pin could be used on one end and a spring tensioned pin 21 on the other end. A construction of this type would take up the end play in the keys and would provide for more ready alignment of the keys and the pivots.

I do not mean to confine myself to the exact details of construction herein disclosed, but claim all variations falling within the purview of the appended claims.

Having thus described my invention, what I claim is:

1. In a key mounting of the kind described, a hinge rod, said rod formed with a concentric bore at each end thereof, a spring in each of said bores and pins slidable in each of said bores, said pins formed with a flat inner end and a rounded outer end and each of said pins formed with longitudinal bore extending inwardly from the tip of said rounded end concentric to said pin and the bore of said hinge rod.

2. A spring pressed pin mounting comprising an elongated tubular member, a cylindrical pin slidable in said tubular member and extensible from an end thereof, a supporting post adjacent an end of said tubular member, said post formed with an outwardly divergent frustro-conical

opening on one side thereof and a reduced diameter bore through said post extending from the apex of said frustro-conical opening, a conical end on said pin engageable in said frustro-conical opening in said post, said pin formed with a concentric bore opening outwardly from the apex of said conical end.

3. A spring pressed pin mounting comprising a supporting post formed with a frustro-conical opening on one side thereof and a reduced diameter bore extending through said post from the apex of said opening concentric thereto, a tubular member open at at least one end thereof, the open end of said member disposed in close proximity to the divergent opening of said post, a spring pressed pin slidable in said member, a conical end on said pin engageable in said frustro-conical opening, said pin formed with a reduced diameter bore opening from the apex of said conical end for registry in alignment with the reduced bore of said post whereby a slender tool may be engaged through said post and in the end of said pin for pressing said pin into said member against the spring tension for removing said member from said post.

4. In a spring pressed pin mounting including a post having an opening therethrough, an open ended member, and a spring pressed pin slidable in said member and extensible into the opening of said post, an end on said pin having an annular configuration corresponding to the inner contour of said opening and said pin formed with a reduced opening at said end opening therefrom whereby a slender tool may be engaged through said post and into said reduced opening to slide said pin into said member against the spring tension for detaching said member from said post.
